SETH L. BECKWITH, OF SAN FRANCISCO, CALIFORNIA.

Letters Patent No. 74,281, dated February 11, 1868.

IMPROVED APPARATUS FOR WASHING GOLD ORES,

The Schedule referred to in these Letters Patent and making part of the same.

TO ALL WHOM IT MAY CONCERN:

Be it known that I, SETH L. BECKWITH, of San Francisco, in the county of San Francisco, and State of California, have invented a new and improved Gold-Washing Machine; and I do hereby declare that the following is a full, clear, and exact description thereof, which will enable those skilled in the art to make and use the same, reference being had to the accompanying drawings, forming part of this specification.

This invention relates to a gold-washing machine, and consists of a washer-pan, hung over a receiver, between the same upright crank-shafts. A simultaneous rotary motion is imparted to the upright crank-shafts, giving to the washer and receiver-pans the peculiar swinging motion adopted in metallurgic-mechanical separation or washing. The washer-pan distributes the earth or gravel, allows the finer particles to pass through with the water, which it pours by its funnel-shaped under portion into the centre of the receiver where it is washed, its overflow, carrying with it the earth and gravel washed to the surface, passes from the inner chambers to the outer, the gold operated upon being retained by its gravity as well as by the overhanging rims, and finally overflows into the outermost vessel, whence it escapes to the ground. This machine is also adapted to dry mechanical separation. In the accompanying drawing—

Figure 1 is a front view, partly in section, of my improved gold-washing machine, and
Figure 2 is a longitudinal section thereof, at line *z z* of fig. 1, with part of the washer-pan broken away to show the lower or receiver-pans.

Similar letters of reference indicate corresponding parts.

A A is the framing, in which the parts of my gold-washing machine are disposed. The upright crank-shafts B B are journalled at *a* and *a*, and are rotated by a power applied to the driving-pulley C, or crank C', through the bevel or mitre-wheels D D d d. The washer and receiver-pans E F G are hung at axial points upon the crank-shafts B, and a rotary motion being imparted to the crank-shafts, every point in the washer and receiver-pans describes a circle, whose radius is equal to the stroke of the crank-shafts B, while the figure described by the periphery of each pan is a circle of radius exceeding its own by the length of stroke of the crank-shafts. The washer-pan E has two bottoms, the upper one arched and perforated, the lower funnel-shaped, and having an opening at its lowest and central portion, as seen in fig. 1. The auriferous earth being placed in pan E, and water poured on, the gold, by its greater specific gravity, falls to the bottom and sides, while the finer particles of earth and gravel, carrying with them some of the gold, are passed with the water through the funnel-shaped bottom *e* into the central chamber *f* of the pan F, which hangs by the crane-arms or brackets *f*, appended to the supporting-bar H, upon the fixed collars *g*, on the crank-shafts B. The rims separating the chambers of the pan F are crowned by an overlapping ridge, as seen in fig. 1 at B.

The continued swinging rotary motion of the pans assists the gold in sinking to the bottom, while the earth and gravel rise to the top, and with the water overflow into the next chamber, and so on to the outermost chamber of pan F, whence they escape into G, and thence, when finally sifted, the earth, gravel, and water, pass away through K. Or the operation may be performed without the use of water at all, with equal accuracy but less rapidity.

I claim as new, and desire to secure by Letters Patent—

1. The device for imparting to the pans E F G the peculiar swinging motion used for separating metals when only mechanically mixed, by hanging them to rotating upright crank-shafts, in manner substantially as and for the purposes above set forth and described.
2. The pan E, provided with a double bottom, whereof the upper one is arched and perforated, and the lower funnel-shaped, in manner substantially as above set forth and described.
3. The pan F, divided into chambers, substantially as above described, the walls whereof are crowned by the overhanging ridges *b*, in manner substantially as above set forth and described.

SETH L. BECKWITH.
